UNITED STATES PATENT OFFICE.

ARTHUR JARRED, OF LONDON, ENGLAND.

CLOCK, WATCH, AND THE LIKE TIMEKEEPING INSTRUMENT.

1,389,666.

Specification of Letters Patent.

Patented Sept. 6, 1921.

Application filed July 29, 1920. Serial No. 399,813.

To all whom it may concern:

Be it known that I, ARTHUR JARRED, a subject of the King of Great Britain and Ireland, residing at London, England, have 5 invented certain new and useful Improvements in and Relating to Clocks, Watches, and the like Timekeeping Instruments, of which the following is a specification.

This invention relates to improvements 10 in clocks, watches, and the like time keeping instruments.

The invention refers more particularly to improvements in clocks, watches and the like of the kind, in which the dial is provided 15 with twenty four indicating numerals, to represent the hours, in lieu of the more usual form in which only twelve hour indicating numerals are used.

In clocks, watches and the like in which 20 the dial is provided with twenty four hour indicating numerals with subdivisions to represent minutes, the numerals, unless considerably reduced, or the dial is enlarged, are of necessity, closely spaced, and consequently lead to confusion.

The object of the present invention is to enable, in this type of clock, watch or the like, numerals of usual size to be employed, without the necessity of increasing the size 30 of the dial, and yet at the same time overcoming the objection of confusion between the numerals.

Another object is to enable the usual clock or watch movement designed for 12 hour 35 periods to be used with the 24 hour indications without alteration in said movement.

According to the present invention a dial having the hour indications arranged to form two sets, one set representing the 40 hours from 1 to 12, and the other the hours from 13 to 24 is disposed behind a second or masking dial provided with windows corresponding in number to the number of indications forming a set, and means, are provided 45 for effecting a relative movement between the dials to enable either one or the other set of indications to be exposed by the apertures, according to the period of the 24 hour day in question.

According to the invention moreover the 50 means for effecting the relative movement between the dials may be automatic, and may be operable by the driving mechanism for the clock, watch or the like.

In the drawings, in which similar refer-

ence numerals indicate corresponding parts throughout the figures;

Figure 1 is a face view of a watch, partly in section, illustrating one form of the invention in which the change of the hour indications is effected manually, 60

Figs. 2 and 3 being a face view and an edge view of a modified form of masking dial for use therewith.

Fig. 4 is a side sectional elevation of a 65 clock and

Fig. 5 a front elevation thereof with part of the dial broken away to expose one form of mechanism for changing the hour indications automatically. 70

Figs. 6, 7, and 8 being detail views of part of the automatic hour indicating changing means in different positions.

Fig. 9 is a front elevation of part of a 75 clock with the dial broken away to show a modified form of automatic means for changing the hour indications.

Figs. 10, 11 and 12 being detail views of part of said automatic hour indication changing means in different positions. 80

Fig. 13 is an enlarged face view of a watch with the dial broken away to show a similar form of automatic hour indication changing means to that shown in Figs. 10 to 12. 85

In the simple form of the invention shown in Figs. 1 to 3 a watch is provided with a primary dial 25 and a secondary or masking dial or mask 26. The primary dial 25 bears two sets of hour indications 1 to 12 90 and 13 to 24 respectively. The hour indications of the two sets are equally spaced around the dial 25, but the hour indications of one set are alternately arranged in relation to those of the other set. The primary 95 dial 25 is capable of an oscillatory movement about its center, the dial 25 being mounted freely on the spindle 36 of the hour hand 28. It is provided with convenient means for effecting such oscillation, for instance, a small finger piece 29 projecting through a slot 30 in the watch case 31, the length of the slot 30 being designed to limit the amount of oscillation in one direction to that sufficient to bring the hour indications, say 1 to 12 coincident with a series of windows 32 in the masking dial 26 to expose the same, and the hour indications 13 to 24 out of coincidence with said windows, 100

namely out of sight behind the mask 26, 110

an oscillatory movement in the opposite direction exposing the hour indications 13 to 24 and masking the other 1 to 12. The user will effect the change of the hour indications manually at an adequate time for example when the minute hand 33 passes the half-hour at 12.30 and 24.30 respectively. The windows 32 may be apertures in the masking dial 26 as indicated in Fig. 1 or may be merely transparencies that is to say portions of a transparent dial 26 which is rendered opaque by painting, gilding or otherwise, except at the windows 32 as indicated in Figs. 2 and 3.

15 The clock illustrated in Figs. 4 and 5 is provided with one form of means for effecting the change of the hour indications automatically. The clock case 34 contains clockwork mechanism of any usual type well known in the art, and is either mechanically or electrically operated, a mechanically operated mechanism being shown more or less diagrammatically as its particular form does not constitute an essential part of the invention and needs no description here beyond the indication that 35 is the usual minute hand spindle, 36 the hour hand spindle, and 37, 38, 39, 40, the usual train of gear wheels which effect the reduction of 12 to 1 in the driving of the hour hand spindle.

30 A small gear wheel 41 on the hour hand spindle 36 meshes with a wheel 42 of double the size, so that the said wheel 42 makes half a revolution for each revolution of the hour hand 28. The wheel 42 is mounted on a spindle 43, suitable carried by the clock frame 44. A wheel 45 fixed on the spindle 43 meshes with another wheel 46 of the same size mounted on a spindle 47 suitably carried by the clock frame 44. Cams 48 and 49 are mounted on the spindles 43 and 47 respectively, and in consequence of the gear wheels 45 and 46 these two cams rotate at the same speed in opposite directions and 40 also at half the speed of the hour hand whereby, for reasons which will be clear hereafter, they effect certain operations at 12 hour periods. In the particular example shown in Figs. 4 and 5 the primary dial 25 is in the form of a spoked wheel. It is provided on one of its spokes with a tappet 50, this particular spoke being omitted in Fig. 5 to expose the parts behind it. The tappet 50 bears alternately on the cams 48, 49, so 50 that the primary dial 25 is held thereby steady in one or the other of the two positions of adjustment with one or the other set of hour indications 1 to 12 or 13 to 24 respectively exposed at the windows 32 in the masking dial 26. The cams 48, 49, have 55 projections 51, 52, respectively. These projections engage respectively with springs 53, 54, so as to tension the same. The springs 53, 54 as shown may be for convenience the two ends of the same piece of steel wire.

coiled about the hub 55 of the primary dial 25. As will be seen from an inspection of Figs. 5 to 8, the cams 48, 49 are set in opposite relation, consequently when one cam is tensioning a spring the other is holding the tappet and therefore the dial steady. Such condition is illustrated by Fig. 6 whereon the projection 51 on the cam 48 is tensioning the spring 53, while the cam 49 is holding the tappet 50 and therefore the primary dial 25 steady against the action of the spring 53, the dial 25 being then in the position corresponding to the exposure of the hour indications 1 to 12. When the cams 48, 49 have rotated so far that the tappet 50 can pass off the larger part or rise of the cam 49, which condition is just about to occur in Fig. 7, the tensioned spring 53 will be effective and oscillate the primary dial 25 to remove the hour indications 1 to 12 from the windows 32 and to bring the hour indications 13 to 24 to the windows 32, this action occurring at half an hour after noon. The cams 48, 49 will then continue to rotate, the projection 52 on the cam 49 ultimately engaging with and tensioning the spring 54 and the cam 48 holding the tappet 50 and therefore the primary dial 25 steady, until the parts, at about half an hour after midnight, reach the position indicated in Fig. 8, wherein the spring 54 is fully tensioned and the tappet 50 is just about to be released by the larger part or rise of the cam 48 to permit of the spring 54 oscillating the primary dial 25 to change the hour indications at the windows 32, namely to remove the indications 13 to 24 and expose the indications 1 to 12.

45 In the form of the invention shown in Figs. 9 to 12 a single cam 48 is used, the primary dial 25 being provided with two tappets 50, 50', adapted to bear on diametrically opposite sides of the cam so that they are released alternately, the springs 53, 54 bearing also diametrically on opposite sides 50 of the cam so that they are alternately tensioned. The action is similar to the foregoing example. In Fig. 9 the primary dial is in the position in which it exposes the hour indications 13 to 24, and the cam 48 is just about to release the tappet 50 to permit the tensioned spring 53 to oscillate the primary dial to expose the hour indications 1 to 12, the cam and allied parts being shown in this position in Fig. 10. A later condition is shown in Fig. 11, while in Fig. 12 the tappet 50' is just about to be released to permit the tensioned spring 54 to oscillate the primary dial to expose again the hour indications 13 to 24. In Fig. 13 a similar form of the invention to that last described is shown applied to a watch the action being identical so that no further description is necessary, the corresponding parts being indicated by similar reference numerals.

I claim:

A time keeping instrument having a primary dial bearing two sets of hour indications, a masking dial to expose either of said hour indications and conceal the other in accordance with the position of the primary dial relative to the masking dial, opposed springs carried by the primary dial and each operative when tensioned to move the primary dial in a direction responsive to such tension, a cam formed to directly engage

and tension said springs in succession at periodic intervals, and members carried by the primary dial to be held by said cam against permitting movement of the primary dial under the spring influence until one of said members and said cam are in a determinate relative position. 15

In testimony whereof I have signed my name to this specification.

ARTHUR JARRED.
